(57) **CLAIM**

The ornamental design for a card box as shown and described.

DESCRIPTION

FIG. 1 is a front, right and top perspective view of a card box, showing our new design;

FIG. 2 is a rear, left and bottom perspective view thereof;

FIG. 3 is a front elevation view thereof;

FIG. 4 is a rear elevation view thereof;

FIG. 5 is a left side elevation view thereof;

FIG. 6 is a right-side elevation view thereof;

FIG. 7 is a top plan view thereof;

FIG. 8 is a bottom plan view thereof;

FIG. 9 is a perspective view of the card box in an alternate configuration;

FIG. 10 is a perspective view of the card box in an alternate configuration;

FIG. 11 is a perspective view of the card box in an alternate configuration; and,

FIG. 12 is a front, right and top perspective view of the card box in an alternate configuration.

In the drawings, the broken lines depict perforations/stitching, which form part of the claimed design. In FIG. 12, the broken line showing of a “tray” depicts unclaimed environmental subject matter.

1 Claim, 12 Drawing Sheets
